UNITED STATES PATENT OFFICE.

JONAS FISCHER, OF WILLIAMSPORT, PENNSYLVANIA.

MACHINE FOR BUNDLING KINDLING-WOOD.

SPECIFICATION forming part of Letters Patent No. 402,428, dated April 30, 1889.

Application filed August 9, 1888. Serial No. 282,347. (No model.)

To all whom it may concern:

Be it known that I, JONAS FISCHER, a citizen of the United States, residing at Williamsport, in the county of Lycoming and State of

5 Pennsylvania, have invented certain new and useful Improvements in Machines for Bundling Kindling-Wood, of which the following is a specification, reference being had therein to the accompanying drawings, in which—

10 Figure 1 represents a vertical sectional view of my improved bundling-machine, the compressing devices being shown in the act of compressing a bundle of sticks; Fig. 2, a front elevation, partly in section, of the standard

15 or support, showing the compressing devices in the position shown in Fig. 1; Fig. 3, a detail perspective view of the vertically-movable cross head or block attached to the standard and pivotally connected to the links of

20 the compressing devices; Fig. 4, a side elevation of the machine, the compressing devices being closed and the pivoted operating-lever locked, as will more fully hereinafter appear; Fig. 5, a rear view of the machine, the parts 25 being in the position shown in Fig. 1; Fig. 6, a plan view of the machine, showing parts in position shown in Fig. 5; Fig. 7, a detail perspective view of a guide for the bundle-ejecting plate; Fig. 8, a side elevation of a portion 30 of the machine, taken from the opposite side from which Fig. 1 is taken; Fig. 9, a detail perspective view of the devices for locking the operating-lever; Fig. 10, a detail perspective view of a portion of the ejecting mechanism; Fig. 11, a perspective view of the U-shaped compressing-block or former, a portion being broken away; Fig. 12, a detail view, partly in section, of the devices illustrated in Fig. 10; and Figs. 13, 14, and 15, detail views 35 that will be more fully hereinafter set forth.

40 My invention has relation to certain new and useful improvements on machines for compressing into compact bundles loose sticks of wood—such, for instance, as sawed kindling-wood—and holding the compressed sticks together while they are tied or bound, and then releasing the tied bundles and automatically ejecting them, as will be more fully hereinafter set forth.

45 50 The object of this invention is to improve and simplify the construction, generally, of the compressing and ejecting devices, where-

by a positively-operating and practical machine that will perform its work rapidly and thoroughly is produced, as will presently appear.

55 As the principle and advantages of this machine will be better understood from a detail description of its construction and operation, I will now proceed to describe it, referring to the accompanying drawings by letters.

60 A designates a suitable base or frame, having erected upon its forward end a standard or support, B, which supports the compressing and forming devices.

65 Journalled in suitable bearings erected on the base A is a transverse shaft, C, provided with a driving-pulley, D, and a cam wheel or disk, E, which is capable of a limited longitudinal movement on the shaft, (being attached thereto by a feather, a,) but rotates with it. This disk is adjusted on the shaft by means of a pivoted angle-lever, F, operated by a pivoted hand-lever, G, the bifurcated end of the angle-lever being provided with suitable pins, which engage an annular groove in a sleeve formed integral with the disk. The lever is limited in its movements by a guard, H, secured to the base.

70 75 It is evident that I may employ other arrangements of shifting-levers without departing from my invention in the least.

75 80 Formed on the face of the disk E is a spiral cam, I, which starts at a point at or near the edge of the disk and terminates near its center, as clearly shown in Figs. 1 and 4. This spiral cam is adapted to engage an anti-friction roller or pin, J, on a lever, K, pivoted at b to the base and provided with an adjustable weight, L. This lever is guided in its vertical movements by means of the guides M, formed integral or bolted to the base, and is limited in its downward movement by the stop N, adapted to abut against a projection, 90 c, on the base. When the spiral cam is thrown by means of the levers into engagement with the pin J on the lever, the same is gradually elevated as the cam-disk is rotated, and as it is moving upward its rear end contacts with the beveled nose of a spring-actuated sliding locking-bar, O, and automatically presses it back until the lever has passed, 95 when it is forced forward by the spring and 100

locks the bar in an elevated position. This locking-bar slides in a suitable bearing or support, P, bolted to the base, and is provided at its rear end with a lateral arm, Q, which has journaled in its face an anti-friction roller adapted to contact with the back of the rotating cam-disk when the same is disengaged from the lever K, as shown in Fig. 6. The arm Q has attached to it a rod, R, which passes through and is supported at its free end by a stationary arm on the base, a spring being interposed between this stationary arm and the movable arm Q, the object of this spring being to keep the locking-bar normally pressed forward.

It is evident that when the cam-disk is disengaged from the lever the disk will, through the medium of the arm Q and anti-friction roller, withdraw the locking-bar and permit the lever to fall, its weight L serving to carry it down quickly and positively. It will also be observed that when the cam-disk is thrown forward into engagement with the lever K the locking-bar will automatically project itself ready to engage the lever when it is brought up again by the cam.

Pivotedly connected to the forward end of the lever K by means of an adjustable clip, S, and a pivotal bolt, d, is the lower end of a connecting-rod, T, the lower end of the connecting-rod being preferably bifurcated to embrace the adjustable clip and lever. By adjusting the clip S along the lever by means of a screw, e, as shown clearly in Fig. 13, the throw of the connecting-rod may be regulated. The upper end of this connecting-rod is tapped into a clip or clevis, f, which is pivotally connected to the rear end of an arm, U, working in a vertical slot in the standard and pivoted between ears g, cast on the face of the same. The forward end of this arm or lever U is provided with ears h, and to these ears are pivoted the inner ends of two toggle-levers, V V. The lower end of the lower one of these levers is pivoted to a sliding cross-head or block, W, provided with a projection or tongue, i, which fits in a vertical slot in the standard, this tongue being held in its slot by means of a plate, j, bolted to it.

The upper end of the upper toggle is pivoted to the lower compressor or former, X, provided with tongues k k, which also fit into vertical guiding-slots in the standard, and are held therein by means of the plates l l, bolted to the tongues and resting against the rear side of the standard. This former or compressor is approximately U-shaped, and is provided with grooves in its vertical edges, and projecting into these grooves from the body of the former are two beveled or inclined lugs, m m, for a purpose hereinafter set forth.

Bolted adjustably by means of bolts n and set-screws p in grooves in the cross-head W are the clips Y Y, and pivotally attached to these clips are the links Z Z. The upper ends of these links are pivotally clamped between the respective ends of two spring-yokes, A'

A', these yokes embracing the former X and resting in the guiding-grooves in its vertical edges, the beveled lugs m being of such a thickness as to pass in between the yokes, as shown in Figs. 1 and 2.

The parts of the compressing and forming devices not heretofore described operate as follows: After the tying-cord has been placed between the yokes and in a groove formed in the upper face of the former, the bunch or bundle of sticks to be compressed and tied is first placed in the former or follower, after which the continuously-rotating cam-disk is thrown into engagement with the pin on the lever K. As this disk revolves in the direction indicated by the arrow on Fig. 1, the rear end of the lever K is elevated and its forward end depressed, carrying with it the connecting-rod T, which in turn pulls down on the arm U. As the rear end of the arm U is depressed, the toggles V V will be forced, respectively, upwardly and downwardly, thus moving the lower former, X, and cross-head W slowly away from each other—that is, the former upwardly and the cross-head downwardly. As the cross-head moves downwardly, it draws the elastic yokes down with it, clamping and compressing into a compact bundle the sticks placed between the movable yokes and U-shaped former. After the bundle is tied the cam-disk is disengaged from the lever K and the lever permitted to drop, in the manner hereinbefore set forth. As the rear end of the lever falls, the forward end of it is elevated and the toggles thereby carried back to their former position, and as the toggles are opened the bundle will be released, the yokes moving upward and the former or follower X being drawn down. As the yokes A' and links Z move upward, the upper inner ends of the latter contact with the beveled lugs m m on the follower, and are thereby forced outward, carrying with them the ends of the yokes, the elastic or spring portion of the yokes permitting this to be done. The object in thus laterally spreading the yokes A' A' is to release the tied bundle, in order that it may be ejected quickly and easily. By this arrangement of the spiral cam and toggle-levers, it will be perceived, a powerful pressure may be exerted upon the bundle, thus bringing the sticks of the bundle into very close contact.

The bundle-ejector is constructed and operated as follows:

The ejector-plate B' has attached to it two rods or pins, q q, which work in guiding sleeves or tubes r r, formed integral with a ring, C', bolted to the rear side of the standard B. This ejector-plate is connected to the vertical arm of an angle-lever, D', by means of a pivotal link, E', which passes through the center of a ring, C', and is pivotally attached to the center of the ejector-plate. The angle-lever is pivoted in ears on the rear side of the standard, and it has its horizontal arm provided with a weight, s. Pivotedly attached to

the weighted arm of the angle-lever and depending therefrom is a curved operating-rod, F', the lower end of which passes through a loop or box, G', bolted to the standard. The 5 rod F', near its lower end, is provided on its side with a beveled lug or enlargement, t, which is adapted at certain times to come in contact with the oppositely-beveled inner walls of the confining-loop G' and throw the lever to one side.

The operation of this ejecting mechanism is as follows: When the bundle has been compressed, tied, and released, and the weighted end of the lever K falls in the manner hereinbefore set forth, the forward end of this lever comes in contact with the lower end of the rod F' and elevates the same. As this rod moves upward, the ejecting-plate, through the medium of the angle-lever and pivotal link, 15 is thrown forward, so as to eject the bundle from the compressing devices. In order to permit the ejecting devices to immediately resume their normal position after each ejection, I provide the rod F' with the beveled 20 lug t. As soon as the lever moves upward far enough to eject the bundle, this lug t contacts with the bevel t', formed on the loop G', and throws the rod F' to one side off of the end of the lever K. When the lower end of 25 the rod F' slips off of the lever K, the weighted angle-lever D' causes the ejecting devices to resume their normal position, as shown in Fig. 1, that portion of the said rod F below the beveled lug t resting against the side of 30 the lever K, as shown in Fig. 12. When the forward end of the lever K is again depressed, the rod F' automatically swings directly over the same, ready for another operation, the said rod F' being sufficiently loosely pivoted 35 to the lever D' to permit this swinging movement of the rod, and the rod being bent, as shown in Fig. 5, to cause it to swing. By means of the adjustable clip S on the lever K and the adjustable clips Y Y on the cross-head W the movement of the compressing devices may be adjusted and the size of the 40 bundle regulated at will.

I do not wish to confine myself to the exact construction and arrangement of parts herein 45 shown and described, as it is evident that persons skilled in the art could vary the same without departing from the scope of my invention.

The advantage in employing a spiral cam 50 to operate the compressing devices is, that the greatest power is obtained where it is most needed. The nearer to the inner end of the spiral cam the pin J gets it is evident that the greater will be the force exerted to elevate the lever K. This maximum of force will be exerted upon the bundle just when the most power is required—that is, when the sticks composing the bundle are being compressed close together.

55 Having thus fully described my invention, what I claim as new, and desire to secure by Letters Patent, is—

1. The combination, with bundle-compressing devices and a pivoted lever, K, connected to the compressing devices by means of a connecting-rod, of the drive-shaft and a rotating disk upon the shaft, this disk being provided with a spiral cam upon its face adapted to engage with the said pivoted lever and gradually elevate the same, substantially as described. 70

2. The combination of bundle compressing and forming devices, a pivoted lever connected to and operating the said compressing devices, a weight on the said lever, a pin, J, 80 secured on the lever, a sliding cam-wheel adapted to elevate the rear end of the lever, and an automatic locking-bar adapted to hold the rear end of the said lever in an elevated position, as and for the purposes set forth. 85

3. The combination of bundle compressing and forming devices, a rod, T, connected to the compressing devices, a pivoted weighted lever, K, a clip, S, pivotally connected to the lower end of the said rod and adjustably connected to the said lever K, and means for elevating the rear end of the said lever K, substantially as described. 90

4. The combination, with bundle-compressing devices, of the pivoted lever K, connected 95 to the bundle-compressing devices and provided with a weight, a cam-wheel for elevating the rear end of this lever, and a sliding beveled locking-bar adapted to hold the said lever in an elevated position, substantially as 100 described.

5. The combination, with the bundle-compressing devices, of the pivoted weighted lever connected to the bundle-compressing devices, a cam for elevating the rear end of the 105 said lever, and an automatic spring-actuated locking-bar provided with a beveled nose, the said bar being provided with a lateral arm, as and for the purposes herein set forth.

6. The combination, with compressing devices, of an ejector-plate, weighted angle-lever pivotally connected to the ejector-plate, a depending rod, F', attached to the angle-lever, a pivoted weighted lever, K, for elevating this rod F', and means for operating the said lever K, substantially as described. 110

7. The combination of ejector-plate, pivoted angle-lever connected to the same, a depending rod, F', connected to the angle-lever, the lower end of this rod being provided with 120 a beveled lug, t, a confining loop or box, G, for the lower end of this rod F', and a pivoted lever for elevating the said rod F', substantially as described.

8. The combination of the sliding former 125 X, the sliding cross-head W, means for moving these parts in opposite directions, yokes A' A', embracing the former X, and pivotal links Z, for connecting the said yokes with the cross-head W, substantially as described. 130

9. The combination of the sliding former X, the sliding cross-head W, toggle-levers for forcing these parts in opposite directions, spring-yokes A' A', embracing the former X,

and pivotal links connecting the ends of the yokes with the cross-head, substantially as described.

10. The combination of a former, X, provided with beveled lugs *m m* on its vertical edges, spring-yokes A' A', embracing the said former and lugs, a sliding cross-head, pivotal links Z Z, connecting the cross-head to the spring-yokes, and means for forcing the cross-head in a downward direction, substantially as described.

11. The combination, with a former, of ver-

tically - movable and laterally - expandable yokes embracing the said former, lugs or projections for expanding the said yokes, pivoted links connected to the said former, and means for operating the yokes, substantially as set forth.

In testimony whereof I affix my signature in presence of two witnesses.

JONAS FISCHER.
